UNITED STATES PATENT OFFICE.

BENJAMIN E. D. STAFFORD, OF PITTSBURGE, PENNSYLVANIA.

CONTAINER FOR COLLAPSIBLE TUBES.

1,382,134.

Specification of Letters Patent. Patented June 21, 1921.

Application filed July 31, 1919, Serial No. 314,416. Renewed May 3, 1921. Serial No. 486,536.

To all whom it may concern:

Be it known that I, BENJAMIN E. D. STAFFORD, a citizen of the United States, and a resident of Pittsburgh, in the county of Allegheny and State of Pennsylvania, have invented certain new and useful Improvements in Containers for Collapsible Tubes; and I do hereby declare the following to be a full, clear, and exact description of the invention, such as will enable others skilled in the art to which it appertains to make and use the same.

My invention relates to an improvement in a container for a collapsible tube.

Many well known toilet and medical preparations and the like are sold in collapsible tubes which are made of a flexible sheet material, and are compressed to eject the contents from a nozzle provided thereon.

The objects of my invention are to provide an ornamental container adapted to receive the ordinary flexible or collapsible tube of commerce, or a specially designed tube, and inclose and protect it and its contents against dirt and injury and which can stand erect on a shelf or table.

A further object of my invention is to provide a container with means whereby the contents of the flexible tube, or any part of the contents may be expelled by the pressure of a finger thereagainst.

With these and other objects in view my invention consists broadly in a container having means for the attachment of a flexible tube and provided with a finger slot or slots.

It further consists in parts and combinations of parts as will be more fully explained and pointed out in the claims.

In the accompanying drawings, Figure 1 is a view in section of one form of my improved container showing an ordinary flexible tube of commerce secured therein; Fig. 2 is a view in elevation of the same showing the finger slot closed; Fig. 3 is a view in elevation of the hood for closing the finger slot in the container; Fig. 4 is a view in section on the line 4—4 of Fig. 1; Fig. 5 is a view in section on the line 5—5 of Fig. 2; Fig. 6 is a view in section on the line 6—6 of Fig. 1; Fig. 7 is a view of the container shown in Fig. 1 with the hood for closing the finger slot on the outside of the container; and Figs. 8 to 14 inclusive are views of modifications.

15 represents the container which in the

construction shown in Fig. 1, consists of a body, preferably cylindrical having an integral head 16 and a removable rear end closure 17. The head 16 is preferably provided with a bead 18 at its juncture with the body of the container, the said bead being preferably milled or otherwise roughened, so that it may be grasped in one hand and held while the end closure 17 is being turned to turn the hood as will be herein-after explained and the periphery of the closure 17 is shaped to conform to said bead so as to present a balanced appearance. This end closure is made flat so as to constitute a base for the container the head 16 is provided centrally with a hole, preferably threaded to engage the external thread on the nozzle 19 on a flexible tube of commerce, and this nozzle projects sufficiently from the head to receive the screw cap 20, which may be the screw cap sold with the collapsible tube or one specially designed for the container. The body 15 of the container is preferably of a size slightly larger than the collapsible tube so as to provide proper support for the latter at all times until the entire contents have been ejected, and it is provided with an elongated finger slot 21, extending lengthwise the body through 75 which the end of a finger or fingers may be inserted for compressing the collapsible tube 22 and ejecting the contents thereof through the nozzle 19.

The end closure 17 is provided with an inwardly projecting circular flange 23 to which the hood 24 is secured. This hood is cylindrical in shape to conform to and snugly fit within the container 15, and is approximately the length of the body of the container so as to close the slot 21 which may and preferably does extend throughout the major part of the length of the latter. The hood 24 is also provided with a slot 25 of the shape and size of the slot 21 in 100 the container 15, so that when the hood is turned, by turning the end closure 17, the finger opening 25 therein will align with the finger opening 21 in the container and expose the collapsible tube 22 which may then be pressed by a finger or fingers of the hand holding the container to eject a part of the contents of the tube.

The hood 24 has a snug fit in the container so that it will be held by friction against 110 accidental endwise displacement or rotary movement, and when not using the con-

tainer the finger opening therein should be closed by turning the hood so as to carry its slot 25 to one side of the slot in the container.

5 Instead of locating the hood within the container as shown in Figs. 1 and 2, it may be on the outside as in Fig. 7, and instead of attaching it to the end closure it may be loose on the container between the beads on 10 the cap and end closure as shown in Figs. 13 and 14.

In Fig. 8 I have shown the cap 16^a made 15 separate from and screwed to the end of container 15^a, and have provided the hood with two finger openings the one 25 extending approximately the length of the container and the other 25^a much shorter and located near the rear end of the container, the shorter one being used when the tube is full 20 or nearly so and the longer one after the tube has been partly exhausted. The short finger opening exposes only a small part of the tube and protects the other part against accidental puncture, when the tube is full 25 and liable to be ruptured by excessive pressure.

In using the device the container is 30 grasped in the hand with the opening 21 therein in a position to receive the ends of the four fingers of the hand holding it, hence by covering a part of the opening so as to expose a smaller surface of the collapsible tube, only one or possibly two fingers of the hand will press against the tube 35 and thus not only minimize the danger of rupturing it, but will also limit the pressure to that of the one or two fingers of the hand holding the container.

In the construction shown in Fig. 11, the 40 head 16^b is provided with a threaded bore 16^c to receive the nozzle 19 of the commercial tube 22, and with an externally threaded nozzle 19^a to receive the cap 20 which may be the cap that goes with the tube 22, of a 45 specially designed cap to go with the container.

In this construction the end closure 17^a 50 may be permanently attached to the body of the container, and in assembling the parts shown in Figs. 11 and 8, the tube 22 is preferably attached to its cap 16^b or 16^c and the latter then secured to the body of the container.

In Fig. 12 I have shown the body of the 55 container 15^b made of glass tubing open at both ends, the head 16^c being cemented or otherwise secured thereto at one end, and the closure 17 secured in or to the other end, and have also shown the nozzle 19^b threaded 60 to engage the cap 16^c and extended in the form of a tube 19^c which may be used for injection, spraying, medicine dropper or other purposes.

It is evident that many slight changes might be resorted to in the relative arrangement of parts shown and described without departing from the spirit and scope of my invention. Hence I would have it understood that I do not wish to confine myself to the exact construction and arrangement of parts 70 shown and described, but

Having fully described my invention what I claim as new and desire to secure by Letters-Patent, is:—

1. A portable container for a collapsible 75 tube comprising a hollow body with a head at one end the latter having a threaded opening to receive the threaded nozzle of a collapsible tube, the nozzle projecting through the head and normally closed by a screw cap, 80 the said container having a finger opening therein whereby the contents of the tube may be ejected through said nozzle and opening by the pressure of a finger against the tube, a closure for the other end of said container, 85 the said closure adapted to be turned and a hood carried by said closure and adapted to be turned by the latter for closing said finger opening.

2. A portable container for a collapsible 90 tube comprising a hollow body having a head at one end and open at the other end, the said head having an opening to receive the nozzle of the tube, and the body having a finger slot extending lengthwise thereof 95 whereby the contents of the tube may be ejected through the nozzle by the pressure of a finger against the tube, a closure for the open end of the container, the said closure being mounted to turn and a hood secured 100 to the closure and located within the container and adapted to be turned with the closure for closing the finger slot in the container.

3. The combination of a container having 105 a head at one end, open at the other end and provided with a finger slot in its side or body, the head having a nozzle opening through the same, a removable closure for the open end of the container, and a collapsible 110 tube having a discharge nozzle projecting through the nozzle opening in the head, the said tube when filled approximately filling the container so as to be supported by the latter while the contents of the tube are 115 being ejected by finger pressure through the slot in the container.

In testimony whereof, I have signed this specification in the presence of two subscribing witnesses.
